(57) **CLAIM**

The ornamental design for a pancake forming plates for pancake baker, as shown and described.

DESCRIPTION

FIG. 1 is a perspective view of a pancake baker, with a pair of opposed mirror image pancake forming plates in accordance with the invention and shown with an associated baker apparatus indicated in phantom;

FIG. 2 is an enlarged top plan view of one of the plates;

FIG. 3 is an enlarged front elevational view of the plate of FIG. 2;

FIG. 4 is an enlarged rear elevational view of the plate of FIG. 2;

FIG. 5 is an enlarged cross sectional view of the plate of FIG. 2, along line 5-5 of FIG. 2; and,

FIG. 6 is an enlarged first side elevational view of the plate of FIG. 2 with a second side elevational view being a mirror image thereof.
